(57) **CLAIM**

The ornamental design for a trash can, as shown and described.

DESCRIPTION

FIG. 1 is an upper front perspective view of a trash can, showing my new design;

FIG. 2 is a front elevation view thereof;

FIG. 3 is a rear elevation view thereof;

FIG. 4 is a top view thereof;

FIG. 5 is a bottom view thereof;

FIG. 6 is a right side elevation view thereof, a left side elevation view being a mirror image thereof;

FIG. 7 is a cross-sectional view thereof taken along lines 7-7 shown in FIG. 2;

FIG. 8 is a cross-sectional view thereof taken along lines 8-8 shown in FIG. 6;

FIG. 9 is a bottom of a lid thereof shown without the body and the bag stopper, for convenience;

FIG. 10 is an enlarged upper perspective view of a bag stopper thereof shown without the body and the lid, for convenience;

FIG. 11 is an enlarged lower perspective view of the bag stopper thereof shown without the body and the lid, for convenience;

FIG. 12 is a front elevation view of the bag stopper thereof shown without the body and the lid, for convenience;

FIG. 13 is a right side elevation view of the bag stopper thereof shown without the body and the lid, for convenience;

FIG. 14 is an upper front perspective view of a body thereof shown without the lid and the bag stopper, for convenience;

FIG. 15 is a top view of the body thereof shown without the lid and the bag stopper, for convenience; and,

FIG. 16 is an upper front perspective view thereof with the lid in an open condition.

The broken lines are included to show portions of the trash can that form no part of the claimed design.

1 Claim, 8 Drawing Sheets
